DRAIN VALVE CONTROL MEANS

Clyde C. Farmer, Pittsburgh, Pa., assignor to The Westinghouse Air Brake Company, Wilmerding, Pa., a corporation of Pennsylvania

Application April 29, 1940, Serial No. 332,143

13 Claims. (Cl. 137—21)

This invention relates to automatic drain valve devices, and more particularly to a drain valve device for use in the drainage system of a refrigerator car and which is automatically operative to retain the drainage system closed so long as the car is in motion.

In the cooling system of refrigerator cars, and especially in those systems where salt is used with ice in the ice bunkers, the drain for disposing of the salt water drippings or brine to the exterior of the car is usually located at the end of and to one side of the car. When salt water drippings or brine is permitted to flow from the drain while the car is traveling over the road, air currents will carry the drippings or brine to many of the metallic parts of the car and railway track, such for instance as the truck parts and to the rail surfaces. The salt in the brine accelerates corrosion of the metallic parts with which it comes in contact, resulting in damage to these parts and thus increases maintenance costs.

The principal object of the present invention is to provide an automatic drain valve apparatus for the drain of a refrigerator vehicle or the like which is operative while the vehicle is in transit to maintain the drain closed and operative to open the drain and permit drainage when the vehicle is traveling at a very slow speed or is at rest.

This object is accomplished in the present embodiment of the invention by a drain valve apparatus having a hydraulic pump, which is responsive to the usual shocks or vibration to which a vehicle is subjected in actual service for automatically closing and maintaining closed the drain at all times while the vehicle is in transit, and which is automatically operative to cause the drain to open and permit drainage from the system when the vehicle is traveling at a very slow speed, such as when it is being brought to rest, or when it is at rest.

Other objects and advantages will appear in the following more detail description of the invention.

In the accompanying drawing Fig. 1 is a sectional view showing a drain valve apparatus embodying my invention.

Fig. 2 is a view in outline showing the drain valve apparatus embodying my invention attached to a car.

As shown in Figs. 1 and 2 of the drawing, the drain valve apparatus comprises a hydraulic pump portion 1 and a drain valve portion 2, both of which are provided with mounting lugs 3 for

attaching the apparatus to the under side of a refrigerator car body in a manner such as shown in Fig. 2 of the drawing.

The hydraulic pump portion 1 comprises an upper section 4, a lower section 5 and an intermediate section 6, which sections are secured together in any suitable manner. The upper section 4 is of tubular form having an open upper end which is normally closed by a closure cap 7 which has screw-threaded connection with the section. The mounting lugs 3 hereinbefore mentioned for mounting the hydraulic portion 1 to the car are located at the upper end of this section and are formed integral therewith.

15 The intermediate section 6 comprises a circular portion which adjacent its periphery is clamped between the sections 4 and 5. This portion together with section 4 and cap 7 define a chamber 8 for the reception of pump actuating means hereinafter described in detail. Carried by the circular portion and depending downwardly therefrom is a pump cylinder 9 which is open at its upper end to the chamber 8. The bottom wall of the cylinder is provided with an inlet port 10 which communicates with a chamber 11 defined by the casing sections 5 and 6, there being a check valve 20 in the cylinder for controlling communication through the port 10.

20 Leading from the interior of the pump cylinder 9 is a passage 12 which is connected to a passage 13 in the section 5. This latter passage leads to a diaphragm chamber 14 located at one side of a flexible diaphragm 15 clamped to the section 5 by a cover portion 16, which cover and diaphragm define a chamber 17. Interposed in the passage 12 and so arranged as to prevent flow from the diaphragm chamber 14 to the cylinder 9 there is provided a ball check valve 18 which is urged to its seat by a spring 19.

25 Disposed in chamber 17 at one side of the diaphragm 15 there is provided a diaphragm follower 21 having a stem 22 which extends to the exterior of the cover portion 16 through an aperture 24. The clearance between stem 22 and

30 the walls of the aperture 24 is sufficient to insure the chamber 17 remaining at atmospheric pressure. Disposed in chamber 14 at the opposite side of the diaphragm 15 there is provided a diaphragm follower 25 which is attached to the diaphragm and diaphragm follower 21 by means of a nut 26 which has screw-threaded engagement with a stem projecting from the follower 22 through the diaphragm 15 and diaphragm follower 25, so that the diaphragm and diaphragm followers 21 and 25 will move as a unit. Con-

tained in chamber 17 is a spring 27 which is interposed between and operatively engages the diaphragm follower 21 and the inner wall of the cover 16 which spring at all times tends to urge the diaphragm assembly to the position shown in Fig. 1 of the drawing.

Operatively mounted in the pump cylinder 9 is a piston or plunger 30 having a stem 31 which extends into the chamber 8 and which carries, at its end, an actuating element 32 which, in the present embodiment of the invention, is in the form of a metal weight 33 preferably formed integral with the plunger stem 31. This weight is yieldingly suspended from the cap 7 by means of a spring 35. One end of the spring 35 is secured to an eye bolt 36 having screw-threaded engagement with the metal weight 33 and the other end attached to an eye bolt 37, which extends through the cap 7 and has the head thereof riveted over, as shown in the drawing.

It is apparent from the foregoing, that when the hydraulic pump portion 1 is mounted on a car, the usual shocks and vibration to which the car is subjected in actual service will cause the spring suspended metal weight 33 to more or less constantly move up and down, thus causing the piston or plunger 30 to reciprocate within the cylinder 9, the spring 35 acting to insure the upward movement of the weight and thereby the piston or plunger 30 relative to the cylinder 9. The body section 4 is provided with longitudinally extending members 38 for guiding the weight 33 in its travel, which members are provided with stop shoulders 39 to limit the upward movement of the metal weight 33, movement of the weight in the opposite direction being limited by the circular wall portion of the intermediate body section 6 with which the weight engages.

The chamber 11 formed in the lower body section 5 of the casing is provided with an oil filling opening 40, through which the chamber 11 is normally filled to the approximate oil level indicated in the drawing, the opening being normally closed by a cap 41 having screw-threaded engagement with the casing.

The drain valve portion 2 comprises a casing having an upper tubular section 43 which is provided at its upper end with a mounting bracket 3 for attachment with a suitable part of the car floor and having further a lower tubular body section 44. The casing sections are secured together by bolts 46 which extend through lugs 47 provided on both sections of the casing and which when thus secured form a chamber 48 therein, there being a gasket 45 interposed between the casing sections 43 and 44. The chamber 48 is in constant communication with the usual drain communication 49 leading from the cooling compartment of a refrigerator car, through a cap 50 which is screw-threaded into the upper open end of the chamber 48.

The bottom of the chamber is provided with a release or discharge passage 51 which may be closed by a valve 52, which valve is adapted to seat on a valve seat 53 formed on an annular shoulder 54 provided on the bottom wall of the body casing section 44. At an intermediate point in the chamber 48 one or more ribs 55 extend laterally from the inside of the casing section 43 and form a central spring seat 56 for the upper end of a spring 57. The other end of this spring seats on the valve 52, which spring at all times tends to urge the valve 52 into seating engagement with its seat 53.

The valve 52 is provided with a fluted stem 58 having an extension 59 which is secured to one end of a vertically disposed link 60 by means of a pin 61. The opposite end of the link 60 is connected to the outer end of a horizontally disposed arm of a bell crank lever 62, which is pivotally connected to a lug 63 projecting from the exterior of the cover 16 on the hydraulic pump portion 1. The other arm 64 of the bell crank lever 62 is vertically disposed and the outer end thereof is forked to receive the end of the diaphragm follower stem 22 which stem and forked end are operatively connected together by means of a pin 65. The points of connection may be slotted to permit relative movement between parts.

In the present embodiment of the invention the hydraulic pump portion 1 and the drain valve portion 2 are separate, however, it will be understood, that the two portions may be formed in one structure if it is so desired.

Operation

Assuming that the vehicle to which the automatic drain valve apparatus is applied is at rest, at which time, the several parts of the apparatus will be in the position in which they are shown in the drawing. It will be observed that the weight 33 and attached piston or plunger 30 will be held at rest, suspended by the spring 35, so that it will not act to displace liquid from the cylinder 9 into the diaphragm chamber 14. However, the liquid supplied to chamber 11 is free to flow therefrom through the passage 67 of small diameter to the chamber 14.

The spring 27 contained in chamber 17 and acting on one side of the flexible diaphragm 15 is sufficient to maintain the diaphragm flexed to the left, as shown, against the opposing pressure of the liquid in chamber 14 at the opposite side of the diaphragm and spring 57 acting on the unseated valve 52. The spring 27 thus acts through the medium of the diaphragm, diaphragm follower, follower stem, bell crank lever and link to maintain the valve 52 open as shown.

When the apparatus is so positioned the usual drain communication 49 leading from the cooling compartment of the refrigerator car is connected to the atmosphere, by way of chamber 48, past valve 52, through release or discharge passage 51, so that drainage from the cooling system is free to flow by gravity to the atmosphere.

When the car is put in motion the spring suspended metal weight 33 for actuating the pump will be caused to move up and down, thus causing the piston or plunger 30 to reciprocate within the cylinder 9. When this occurs the piston or plunger 30 on its suction or upward stroke sucks oil from the chamber 11 through port 10, past ball check valve 20 to the cylinder 9. It might be here mentioned that the portion of the chamber 11 above the oil lever is connected to chamber 8 by way of a passage 66 to insure chamber 11 remaining at atmospheric pressure.

The ball check valve 20 is adapted to close the communication through port 10 from chamber 11 to the cylinder 9 upon the completion of the suction or upward stroke of the piston or plunger 30. Upon initial movement of the piston or plunger 30 in its compression or downward stroke the ball check valve 20 is forced more firmly to its seat and the fluid within the cylinder 9 is forced past ball check valve 18 into passage 12 and conducted by way of passage 13 to the diaphragm chamber 14, from whence it is returned to chamber 11.

ber 11 by way of passage 67. On each successive suction stroke of the piston or plunger 30 the check valve 18 is seated by spring 19 and as a result, the pressure within the diaphragm chamber 14 increases and the oil supplied to the chamber causes the diaphragm 15 to flex to the right against the action of the spring 27, because the capacity of the pump is many times the flow capacity of the passage 67. When the diaphragm is flexed to the right it acts through the medium of the diaphragm followers 21 and 25, follower stem 22, bell crank lever having arms 64 and 62 and links 60 to move the valve 52 toward engagement with its seat 53, permitting the spring 57 to maintain the valve 52 seated, thus cutting off communication between the usual drain communication 49 and the atmosphere, through release or discharge passage 51.

So long as the car is in motion, the valve 52 will remain closed and any drainage from the usual drainage communication 49 leading from the cooling compartment of the car, will be trapped in the chamber 48 of the drain valve portion 2.

When the car is traveling at a very slow speed such as when being brought to or is at rest, movement of the weight 33 will stop, and the spring 35 will again suspend the weight 33 and attached piston or plunger 30 in its upper position as shown, thus cutting off the supply of liquid to the diaphragm chamber 14. When this occurs the passage 67 connecting chambers 14 and 11 will permit the fluid under pressure acting on the diaphragm 14 to flow to the chamber 11, and spring 27 will then flex the diaphragm 15 to the left, which as hereinbefore described, causes the valve 52 to open. With the car at rest and the valve 52 open any drainage accumulated in chamber 48 will now be released to the atmosphere.

It will be seen that this drain valve apparatus operates automatically to drain the cooling system of a refrigerator car as the car is brought to rest and operates to maintain the drain closed when the car is in motion, and that it is a relatively simple apparatus requiring no attention on the part of the train crew.

While the automatic drain valve apparatus has for illustrative purposes been shown exteriorly of the car it is contemplated that it may also be used interiorly of a car.

While one embodiment of the drain valve apparatus provided by my invention has been illustrated and described in detail, it should be understood that the invention is not limited to these details of construction, and that numerous changes and modifications may be made without departing from the scope of the following claims.

Having now described my invention, what I claim as new and desire to secure by Letters Patent, is:

1. In a drainage system for draining liquid from the interior of a refrigerator vehicle or the like comprising a drainage discharge communication, means operative to either open or close said communication, and means operative automatically only when the vehicle is in transit for effecting the operation of the first mentioned means to close said communication and operative automatically only when the vehicle is brought to rest for effecting the operation of the first mentioned means for opening said communication.

2. In a drainage system for draining liquid from the interior of a refrigerator vehicle or the like comprising a drainage discharge communication, pressure responsive means operative to

either open or close said communication, and means operative automatically only when the vehicle is in transit for effecting the operation of said pressure responsive means to close said communication and operative only when the vehicle is brought to rest for effecting the operation of the pressure responsive means for opening said communication.

3. In a drainage system for draining liquid from the interior of a refrigerator vehicle or the like comprising a drainage discharge communication, hydraulically actuated means operative to either open or close said communication, and means operative automatically only when the vehicle is in transit for effecting the operation of said hydraulically actuated means to close said communication and operative only when the vehicle is brought to rest for effecting the operation of the hydraulically actuated means for opening said communication.

4. In a drainage system for draining liquid from the interior of a refrigerator vehicle of the like comprising a drainage discharge communication, means operative to either open or close said communication, and inertia actuated means operative automatically only when the vehicle is in motion for effecting the operation of the means to close said communication and operative only when the vehicle is at rest for effecting the operation of the means for opening said communication.

5. In a drainage system for draining liquid from the interior of a refrigerator vehicle or the like comprising a drainage discharge communication, means operative to either open or close said communication, and means including an inertia actuated pump operative automatically only when the vehicle is in motion for effecting the operation of the means to close said communication and operative only when the vehicle is at rest for effecting the operation of the means for opening said communication.

6. In a drainage system for draining liquid from the interior of a refrigerator vehicle or the like comprising a drainage discharge communication, means operative to either open or close said communication, a pump operative only when the vehicle is in motion for effecting the operation of the means to close said communication and operative only when the vehicle is at rest for effecting the operation of the means to open said communication, and inertia actuated means for actuating said pump, said inertia actuated means comprising a yieldingly suspended weight responsive to the usual shocks to which the vehicle is subjected in transit.

7. In a drainage system for draining liquid from the interior of a refrigerator vehicle or the like comprising a drainage discharge communication, means operative to either open or close said communication, a pump operative only when the vehicle is in motion for effecting the operation of the means to close said communication and operative only when the vehicle is at rest for effecting the operation of the means to open said communication, and inertia actuated means for actuating said pump, said inertia actuated means comprising a yieldingly suspended weight responsive to the usual shocks to which the vehicle is subjected in transit, and means for limiting the travel of said weight.

8. In a drainage system for draining liquid from the interior of a refrigerator vehicle or the like comprising a drainage discharge communication, pressure responsive means operative to

either open or close said communication, a hydraulic pump for effecting the operation of the pressure responsive means, said pressure responsive means being operative to close said communication while the pump is operating and operative to open said communication while the pump is at rest, and inertia actuated means for actuating said pump while the vehicle is in transit.

9. In a drainage system for draining liquid from the interior of a refrigerator vehicle or the like comprising a drainage discharge communication, a valve operative to either open or close said communication, pressure responsive means operative automatically for controlling the operation of said valve, and means including a pump operative when the vehicle is in transit for effecting the operation of the pressure responsive means to cause operation of said valve to close said communication, said means being rendered inoperative when the vehicle is brought to rest for effecting the operation of the pressure responsive means to cause said valve to open said communication.

10. In a drainage system for draining liquid from the interior of a refrigerator vehicle or the like comprising a drainage discharge communication, a valve operative to either open or close said communication, means including an inertia actuated pump operative while the vehicle is in transit and inoperative while the vehicle is being brought to rest, said means being responsive to the usual shocks to which the vehicle is subjected in transit for supplying fluid under pressure, pressure responsive means comprising a movable abutment responsive to the pressure of fluid supplied by said pump for effecting operation of said valve to close said communication and subject to the pressure of a spring for effecting operation of said valve to open said communication, and means for reducing the pressure of fluid acting on said abutment when the pump is brought to rest.

11. In a drainage system for draining liquid from the interior of a refrigerator vehicle or the like comprising a drainage discharge communication, a valve operative to either open or close said communication, a pump comprising a cylinder having an inlet port and an outlet port, a pump plunger operatively mounted in said cylinder for first drawing fluid through said inlet port to the cylinder and for then forcing the fluid from the cylinder through said outlet port, means comprising an inertia element automatically operative when the vehicle is in transit for operating the pump and rendered inoperative to operate the pump when the car is brought to rest, means

including a movable abutment responsive to the pressure of fluid supplied by said pump when operating for effecting the operation of said valve to close said communication, and responsive to the pressure of a spring upon a reduction in the pressure of fluid acting on the abutment for effecting operation of said valve to close said communication, and means for relieving the pressure of fluid acting on said abutment when said pump is stopped.

12. In a drainage system for draining liquid from the interior of a refrigerator vehicle or the like comprising a drainage discharge communication, in combination, a drain valve apparatus including a pump comprising a casing having a pump chamber and an oil supply chamber, said pump chamber having an inlet port through which oil is supplied from said oil chamber to said pump chamber and an outlet passage through which oil is discharged from said pump chamber, a pump plunger operatively mounted in said pump chamber, means included in said pump operative on the suction stroke of said plunger for opening said inlet port and closing said outlet port to reverse flow to the pump chamber and operative on the compression stroke to close said inlet port and permit the flow of oil through said outlet port, means comprising an inertia element automatically operative when the car is in transit for operating said pump and rendered inoperative to operate the pump when the vehicle is at rest, and pressure responsive means operative when the pump is operating to effect closing of said discharge communication and operative when the pump is stopped to effect the opening of said discharge communication.

13. In a drainage system for draining liquid from the interior of a refrigerator car or the like comprising a drainage communication, a valve operative to either open or close said communication, means yieldingly holding said valve in closed position, yielding means for holding said valve open, an inertia actuated hydraulic pump, operative when the vehicle is in motion and rendered inoperative when the vehicle is at rest, said pump when operative circulating fluid under pressure, a movable abutment subject to and actuated by the pressure of fluid circulated by the pump for rendering said means ineffective to hold said valve closed, and means for relieving the pressure of the circulating fluid acting on the abutment when the vehicle is at rest for rendering said yielding means effective to hold said valve open.

CLYDE C. FARMER.
